CONTAINER

Carl A. Nesmith, Los Angeles, Calif.

Application May 16, 1938, Serial No. 208,212

8 Claims. (Cl. 220—42)

This invention relates to receptacles or containers, and it is a general object of the invention to provide a simple, practical and effective container that is particularly easy to open and manipulate.

The containers in which pastes, salves, polishes, etc. are packaged and sold usually embody either screw caps or pressed-on closures. Such caps or closures are very difficult to remove and the user often injures his hands in attempting to turn or pry them loose.

Another object of this invention is to provide a container embodying a closure or cover that may be easily freed for removal by merely pressing down upon it.

Another object of the invention is to provide a container in which the closure or cover may be quickly removed without tapping, turning or prying and, therefore, without danger of injuring the hands or mutilating the container parts.

Another object of this invention is to provide a readily opened container of the character mentioned that is air tight and fluid tight to fully preserve the contents.

Another object of the invention is to provide a container that embodies an outer tubular member associated with the top or closure and shiftably telescopically related to the container body in such a manner that pressure applied downwardly against the cover moves the body down relative to said member to free or disconnect the cover and member assembly from the container body whereupon the body and its contents may be immediately made fully accessible.

Another object of this invention is to provide a container of the character mentioned in which the tubular outer member and the top or closure are loosely connected to form a single unit when removed from the body to facilitate the handling of the container and the re-application of the cover to the container body.

A further object of this invention is to provide a container of the character mentioned embodying novel and improved means for releasably retaining the tubular member on the body in a position where the cover is tightly held in place to maintain a fluid tight and air tight seal.

The various objects and features of my invention will be fully understood from the following detailed description of typical preferred forms and applications of the invention, throughout which description reference is made to the accompanying drawing, in which:

Fig. 1 is a top or plan view of the improved container provided by this invention. Fig. 2 is

an enlarged side elevation of the container with a portion broken away to illustrate the several parts in vertical cross section. Fig. 3 is an enlarged fragmentary vertical detailed sectional view of the container in the closed condition. Fig. 4 is a reduced vertical detailed sectional view with the body and closure in elevation and showing the body and closure in the positions that they assume after a pressure has been applied to the cover to free the same. Fig. 5 is a view similar to Fig. 4 showing the cover and the tubular member being lifted from the body. Fig. 6 is an enlarged fragmentary sectional view illustrating a slightly modified form of detent means, and Fig. 7 is a fragmentary elevation view of the detent means shown in Fig. 6.

The container of the present invention illustrated in Figs. 1 to 5, inclusive, of the drawing, includes, generally, a body 10, a top or closure 11 for the body 10, a shell or member 12 associated with the closure 11 and telescoping over the body 10 to support the body, and a releasable connection or detent means 13 holding the member 12 against movement in a position where the cover 11 is tightly closed and releasable by downward movement of the cover and body 10 relative to the member 12.

The container body 10 is provided to contain the product or material packaged in the container. In the drawing the body 10 is a simple cup-like member having a flat bottom 14 and a generally cylindrical side wall 15 extending upwardly from the bottom 14. It is to be understood that the container body 10 may be of other shapes, for example, it may be polygonal in cross section. The body 10 may be formed of metal that is tinned, plated or otherwise treated, it being understood that the body may be formed of any suitable material. In the preferred construction an annular inwardly projecting flange 16 is provided on the upper end of the side wall 15. The flange 16 is preferably flat and generally horizontal. A rolled bead 17 may be formed on the inner edge of the flange 16 to remove or eliminate the sharp edge of the flange.

The top or closure 11 is provided to normally seal or close the open upper end of the container body 10. The closure 11 may be constructed of the same material as the body 10. In the typical form of the invention illustrated the closure 11 is a simple disc-like member provided with an annular down-turned peripheral wall part 18. The wall part 18 is curved or convex in external configuration to give the closure 11 a dome-like appearance. If desired or believed

necessary the closure 11 may be corrugated to increase its rigidity. An internal or inwardly projecting annular flange 19 is provided at the lower end of the wall part 18. The flange 19 is flat and generally horizontal and opposes the flange 16 on the body 10. A bead or roll 20 is preferably formed on the inner edge of the flange 19. The flanges 16 and 19 may be of the same internal diameter and their beads or rolls 17 and 20 are turned or rolled in opposite directions so that they do not engage or interfere with one another. The flange 19 may be of larger outside diameter than the flange 16 to extend outwardly beyond the flange 16.

15 It is preferred to provide a sealing gasket or washer 21 to seal between the flanges 16 and 19. The washer 21 may be a simple annular part of rubber, cardboard or other suitable material and may be secured to the flange 16 or the flange 19. 20 In the present instance it will be assumed that the sealing washer 21 is cemented or otherwise secured to the flange 19. When the container is closed the washer 21 forms or provides a dependable fluid-tight and air-tight seal between 25 the flanges 16 and 19 to preserve the contents of the container. In accordance with the invention the cover or closure 11 has an annular outwardly turned or outwardly projecting annular ridge or rim 22. The rim 22 may occur where 30 the wall part 18 joins the flange 19. The rim 22 may be formed by suitably bending or shaping the material of the closure 11. The rim 22 is shaped to constitute or present an upwardly facing annular shoulder part on the closure 11.

35 The shell or outer member 12 normally surrounds or engages about the container body 10 and is coupled or connected with the closure 11 to normally hold the same in its closed position. The member 12 is a slightly tapered tubular element adapted to surround the side wall 15 of the container body 10. In practice the member 12 is formed of metal of suitable gauge to have the desired flexibility and resiliency. The external surface of the shell or member 12 may serve to 40 carry the label, printing, etc., it being obvious that the top surface of the closure 11 may also be employed for this purpose. In accordance with the invention the member 12 is longer or of greater vertical extent than the body 10 to 45 project beyond the upper and lower extremities of the body.

It is preferred to construct and relate the parts so that the body 10 and the member 12 have sealing and frictional engagement. Where the 50 side wall 15 of the body 10 is cylindrical or vertical, as above described, a portion X of the member 12 is flared or tapered upwardly and inwardly at a decreased angle to have its inner surface cooperate with the external surface of the body wall 15 when the container is closed. In practice the portion X of the member 12 seals with the wall 15 adjacent the upper end of the wall. The portion X of the member 12 is annular to seal with and frictionally engage the 55 wall 15 throughout the circumference of the body wall 15. The portion of the member 12 below its portion X may be shaped and proportioned to have suitable clearance with the external surface of the body wall 15 when the container is in its normal closed condition. The lower portion of the member 12 which projects downwardly beyond the bottom 14 of the body 10 is preferably provided with a roll or base bead 23 for engaging against a support to carry or support the container. The rim or bead 23 is

preferably provided on the outer side of the member 12 so that it does not interfere with the movement of the member 12 over the body 10.

In accordance with the invention the member 12 is coupled or connected with the closure 11 to normally hold it in its closed position. The member 12 is bent outwardly or extends outwardly in a plane below its upper end to have an upwardly facing annular shoulder 24. A substantially cylindrical wall portion 25 extends 10 upwardly from the shoulder 24. When the container is closed the shoulder 24 is spaced below the upper end of the container body wall 15. The wall portion 25 receives or surrounds the rim 22 of the closure 11. An internal bead 26 15 is provided on the upper end of the wall portion 25 to cooperate with the rim 22. The bead 26 is located and shaped to bear against the upper side of the rim 22. When the member 12 is secured to the body 10 by the means 13, as will 20 be subsequently described, the bead 26 cooperates with the rim 22 to urge or hold the closure 11 down so that the washer 21 is tightly gripped between the flanges 16 and 19 to form or provide a tight seal. When the container is open, 25 that is, when the closure 11 and the member 12 are removed from the body 10 the shoulder 24 and the bead 26 limit movement of the rim 22 and the washer 21 relative to the member 12 and thus prevent separation or disconnection of 30 the closure 11 from the member 12.

The means 13 is in the nature of a releasable detent means for normally holding the parts in the positions illustrated in Figs. 2 and 3 of the drawing where the bead 26 bears downwardly 35 against the rim 22 to hold the cover or closure 11 in its closed position. The means 13 is capable of considerable variation and modification. In the typical form of the invention illustrated in Figs. 1 to 5, inclusive, of the drawing, 40 the means 13 includes an annular groove 28 in the inner side or the internal surface of the member 12 and an annular outwardly projecting ridge or bead 29 on the container body wall 15 for cooperating with the groove 28. The groove 45 28 may be readily formed by bending or shaping the material of the member 12 and the bead 29 may be formed on the body wall 15 in a similar manner. The groove 28 is preferably spaced above the bead 23 and the detent bead 29 is at 50 or adjacent the line of connection of the wall 15 with the bottom 14 of the body 10. Thus when the container is in the closed condition with the bead 29 cooperating with the groove 28, the bottom 14 of the body 10 is spaced above the support on which the detent is resting. This will be evident from an inspection of Figs. 2 and 3 of the drawing. The bead 29 need not closely fit the groove 28 but may merely bear on the lower wall portion of the groove.

When a downward pressure or force is applied to the closure 11 it is transmitted to the body 10 through the washer 21 and the flange 16 and if of sufficient intensity will cause the member 12 to flex or expand so that the bead 29 snaps 65 down out of the groove 28. The body 10 and closure 11 are then in the positions illustrated in Fig. 4 of the drawing and the member 12 may be readily slid up over the body, as shown in Fig. 5. The bead 29 is adapted to snap into 70 the groove 28 to hold the closure 11 in the closed position when the closure 11 and the member 12 are moved down on the body 10. The cooperation of the bead 29 with the groove 28 maintains the bead 26 in engagement with the rim 75

22 to hold the cover or closure 11 tightly closed and maintains the wall portion X of the member 12 in sealing and frictional engagement with the body wall 15. 5
 5. Figs. 6 and 7 of the drawing illustrate another form of holding means or detent means for holding the parts in the normal closed positions where the closure 11 is held down and the wall portion X engages with the body wall 15. In this construction the detent means 13^a includes the bead 29 on the body 10 which may be as described above. One or more projections 30 are provided on the member 12 for cooperating with the bead 29. It may be preferred to provide two or more 10 circumferentially spaced projections 30 on the member 12. The projections 30 are in the nature of lugs projecting from the inner surface of the member 12 for engaging upwardly against the under side of the bead 29. In practice the projections 30 may be elongated circumferentially 15 of the member 12. The wall of the member 12 is preferably slotted to allow the projections 30 to more readily snap into and out of cooperation with the bead 29. As illustrated there may be 20 two spaced vertically extending slots 31 provided in the member 12 adjacent each projection 30. The slots 31 are spaced from the opposite ends of the projections 30 so that the metal between the slots forms springs that flex to allow the projections 30 to snap into and out of holding 25 engagement with the bead 29. The parts are proportioned and related so that the engagement of the projections 30 with the bead 29 maintains the member 12 in the position where the cover or closure 11 is held tightly closed and the portion 30 X properly cooperates with the body wall 15.

It is believed that the utility and practicability of the improved container of the present invention will be readily understood from the foregoing detailed description. When it is desired to open the container the container is placed on a suitable support so that the bead 23 rests on it to support the container. A downward force or pressure is then put on the closure 11. This downward force is transmitted through the flange 19, the washer 21 and the flange 16 to the body 10. The downward force on the body 10 acting through the engagement of the bead 29 with the wall of the groove 28 or by the engagement 40 of the bead 29 with the projections 30 tends to spread or expand the member 12 and when a sufficient downward force is applied the bead 29 snaps down out of the groove or past the projections 30 as the case may be. The body 10 and the closure 11 are thus free to move down to positions such as shown in Fig. 4 of the drawing where the bottom 14 of the body engages against the support. The member 12 carrying the closure 11 may then be freely slid up off the body 10, as 45 illustrated in Fig. 5. It will be observed that the cover or closure 11 is carried by the member 12 and is removed from the body 10 together with the member. The removal of the member 12 from the body 10 fully exposes the upper end of 50 the body rendering the contents of the container accessible.

When it is desired to reclose the container the member 12 is passed down around the body 10 or the body 10 is moved upwardly into the member 12. The body 10 and the member 12 are moved longitudinally with respect to one another until the bead 29 snaps into the groove 28 or the projections 30 snap under the bead 29 as the case may be. This reconnects or re-secures the member 12 to the body 10 and retains the closure 11 55

in the position where its flange 19 tightly seals against the washer 21 and the washer seals with the flange 16. The wall portion X of the member 12 is also brought to sealing and frictional cooperation with the exterior of the body wall 15.

The present invention provides a container in which the closure or cover 11 may be easily and quickly freed for removal by merely pressing down upon it. When the container is resting on 10 a stationary support the user may place a substantial downward force on the closure 11 with a minimum of effort to release the detent means 13 or 13^a and thus free the closure 11 for removal. The container is dependably sealed by the washer 15 15 gripped between the flanges 16 and 19 and by the engagement of the wall portion X of the member 12 with the body wall 15. The container of the present invention is inexpensive and is particularly convenient to use. 20

Having described only typical preferred forms and applications of my invention, I do not wish to be limited or restricted to the specific details herein set forth, but wish to reserve to myself any variations or modifications that may appear 25 to those skilled in the art or fall within the scope of the following claims.

Having described my invention, I claim:

1. A container comprising a container body, a cover adapted to bear downwardly on the body 30 to close the same, a tubular member around the body, the upper and lower ends of the member being open, a part on the tubular member normally cooperating with the cover to hold it down on the body, said member extending down around 35 the body to project from its lower end to rest on a support so that a downward force applied to the cover may move the cover downwardly from said part to be readily removable from the body, means holding the member on the body in the 40 position where the cover is closed and releasable by said downward force, and a second part on the tubular member spaced below the first named part and cooperable with the cover to limit downward movement of the cover relative to the member, 45 said parts permanently slackly connecting the cover and tubular member for removal and handling as a unit.

2. A container comprising a container body, a cover adapted to bear downwardly on the body 50 to close the same, a tubular member around the body, a rim on the cover, vertically spaced shoulders on the member between which said rim is received whereby the cover is loosely coupled with the member, one of said shoulders normally co- 55 operating with the rim to hold the cover closed, the member extending beyond the lower end of the body so that a downward force on the cover may move the cover and body down relative to the member to free the rim from the said shoulder, and means holding the body and member against relative movement releasable by said downward force.

3. A container comprising a container body, a cover adapted to bear downwardly on the body 65 to close the same, a tubular member around the body, a rim on the cover, vertically spaced shoulders on the member between which said rim is received whereby the cover is loosely coupled with the member, one of said shoulders normally co- 70 operating with the rim to hold the cover closed, the member extending beyond the lower end of the body so that a downward force on the cover may move the cover and body down relative to the member to free the rim from the said shoulder. 75

der, and means holding the body and member against relative movement releasable by said downward force, said means including a bead on the body, and a detent projection on the member cooperable with the bead.

5. A container comprising a container body, a cover adapted to bear downwardly on the body to close the same, a tubular member around the body, a rim on the cover, vertically spaced shoulders on the member between which said rim is received whereby the cover is loosely coupled with the member, one of said shoulders normally cooperating with the rim to hold the cover closed, the member extending beyond the lower end of the body so that a downward force on the cover may move the cover and body down relative to the member to free the rim from the said shoulder, and means holding the body and member against relative movement releasable by said downward force, said means including a bead on the body, and a wall portion on the member defining a groove for receiving the bead.

6. A container comprising a container body, a cover adapted to bear downwardly on the body to close the same, a tubular member around the body, a rim on the cover, vertically spaced shoulders on the member between which said rim is received whereby the cover is loosely coupled with the member, one of said shoulders normally cooperating with the rim to hold the cover closed, opposing flanges on the body and cover, a sealing washer engaged between the flanges, the member extending beyond the lower end of the body so that a downward force on the cover may move the cover and body down relative to the member to free the rim from the said shoulder, and means holding the body and member against relative movement releasable by said downward force.

7. A container comprising a container body, a cover adapted to bear downwardly on the body to close the same, a tubular member around the body, a rim on the cover, vertically spaced shoulders on the member between which said rim is received whereby the cover is loosely coupled with the member, one of said shoulders normally cooperating with the rim to hold the cover closed, the member extending beyond the lower end of the body so that a downward force on the cover may move the cover and body down relative to the member to free the rim from the said shoulder, and means holding the body and member against relative movement releasable by said downward force, said means including a bead on the body, and a detent projection on the member

cooperable with the bead, the member having spaced slots at opposite sides of the detent projection whereby the projection may spring into and out of cooperation with the bead.

7. A container comprising a container body, a cover adapted to bear downwardly on the body to close the same, a tubular member around the body, a bead part on the upper edge of the tubular member bearing downwardly against the peripheral portion of the cover to hold the same closed, the cover being directly manually accessible at the upper end of the container, a tapered internal surface on the member normally cooperating with the body, the member extending downwardly beyond the lower end of the body to rest on a support so that a down pressure on the cover may move the body and cover down relative to said member to free the cover from said part, means for holding the member in the position where its said part cooperates with the cover, releasable by the said down pressure, and a second part on the tubular member spaced from the bead part and adapted to cooperate with the under surface of the peripheral portion of the cover to limit the downward movement of the cover relative to the tubular member, the cooperation of said parts with the cover permanently slackly connecting the cover and tubular member for removal and handling as a unit.

8. A container comprising a container body, a cover for the body having a rim whose under side is adapted to contact the upper edge of the body, a tubular member around the body extending from above the upper edge of the body to below the lower end of the body, the upper and lower ends of the member being open, means adjacent the lower end of the member for releasably supporting the body to hold the lower end of the body above the lower end of the member, and a part on the upper end of the member loosely receiving the rim to connect the member and cover for limited relative movement lengthwise of the container and presenting a surface which bears downwardly on the rim to hold the rim against the upper end of the body when the body is supported by said means whereby a downward push applied to the cover may move the cover and body downwardly relative to the member to release said means and thus allow withdrawal of the body through the lower end of the member, said part cooperating with the rim to retain the cover in the member upon such withdrawal of the body.

CARL A. NESMITH.
